US00D731051S

(12) **United States Design Patent**
Olson et al.

(10) **Patent No.:** US D731,051 S
(45) **Date of Patent:** ** Jun. 2, 2015

(54) **DRUG DELIVERY DEVICE**

(71) Applicants: **Lorin Olson**, Scotts Valley, CA (US); **Peter Krulevitch**, Pleasanton, CA (US); **Nicholas Foley**, Edinburgh (GB); **James Glenecross**, Edinburgh (GB); **Rochelle Kleinberg**, New York, NY (US); **David Shepherd**, Edinburgh (GB)

(72) Inventors: **Lorin Olson**, Scotts Valley, CA (US); **Peter Krulevitch**, Pleasanton, CA (US); **Nicholas Foley**, Edinburgh (GB); **James Glenecross**, Edinburgh (GB); **Rochelle Kleinberg**, New York, NY (US); **David Shepherd**, Edinburgh (GB)

(73) Assignee: **Janssen Biotech, Inc.**, Malvern, PA (US)

(**) Term: **14 Years**

(21) Appl. No.: **29/449,399**

(22) Filed: **Mar. 15, 2013**

(51) LOC (10) Cl. **24-02**

(52) U.S. Cl.

USPC **D24/114**

(57) **CLAIM**

The ornamental design for a drug delivery device, as shown and described.

DESCRIPTION

This application is related by subject matter to U.S. patent application Ser. No. 29/370,686, filed Aug. 19, 2010 and to U.S. patent application Ser. No. 29/370,687, filed Aug. 19, 2010.

FIG. 1 is a top, left, front perspective view of a drug delivery device according to an embodiment of our design, the drug delivery device being shown in a pre-use position;

FIG. 2 is a top, left, rear perspective view thereof;

FIG. 3 is a bottom, left, rear perspective view thereof;

FIG. 4 is bottom, right, front perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is a top, left, front perspective view of the drug delivery device shown in FIG. 1 in a post-use position;

FIG. 12 is a bottom, right, rear perspective view thereof;

FIG. 13 is a front elevation view thereof;

FIG. 14 is a rear elevation view thereof;

FIG. 15 is a left side elevation view thereof;

FIG. 16 is a right side elevation view thereof;

FIG. 17 is a top plan view thereof;

FIG. 18 is a bottom view thereof;

FIG. 19 is a bottom plan view taken along the line 19-19 shown in FIG. 13; and,

FIG. 20 is a top plan view taken along the line 20-20 shown in FIG. 13.

The broken line portion of the figure drawings is included to show unclaimed subject matter only for the purpose of illustrating environment and forms no part of the claimed design.

1 Claim, 9 Drawing Sheets
